United States Patent Office.

JOSEPH T. CAPEWELL, OF WOODBURY, CONNECTICUT.

Design No. 4,972, dated June 6, 1871.

DESIGN FOR SHOT-POUCH, &c.

The Schedule referred to in these Letters Patent and making part of the same.

I, JOSEPH T. CAPEWELL, of Woodbury, Litchfield county, in the State of Connecticut, have invented and produced a new and original Design to be placed upon Shot-Pouches, Powder Flasks, and Game-Bags.

The nature of my invention is fully illustrated in the accompanying drawing, to which reference is made.

Of the two illustrations one is to be placed upon

one side of the pouch, flask, or bag, the other on the other, stamped, or printed, or embossed.

What I claim as my invention is—
The duplex design herein shown.

JOSEPH T. CAPEWELL.
